[57] CLAIM

The ornamental design for seating furniture, as shown and described.

DESCRIPTION

FIG. 1 is a front perspective view of seating furniture according to my new design and as a first embodiment showing a lounge chair;

FIG. 2 is a front elevational view thereof;

FIG. 3 is a back elevational view thereof;

FIG. 4 is a side elevational view thereof, the opposite side being a mirror image;

FIG. 5 is a front elevational view of the seating furniture according to my design and as a second embodiment showing a sofa and excluding the line detail at the base thereof;

FIG. 6 is a back elevational view thereof; and,

FIG. 7 is a side elevational view thereof, the opposite side being a mirror image.
